(57) **CLAIM**

The ornamental design for an amusement ride, as shown and described.

DESCRIPTION

FIG. 1 is a fragmented perspective view of an amusement ride showing my new design, the identical ride being omitted for ease of illustration only;

FIG. 2 is a front view thereof;

FIG. 3 is a rear view thereof;

FIG. 4 is a perspective view thereof of the amusement ride disclosed in FIG. 1, the undisclosed opposite side being a mirror image;

FIG. 5 is a fragmented perspective view of a second embodiment of the amusement ride showing my new design, the identical ride being omitted for ease of illustration only;

FIG. 6 is a front view of FIG. 5;

FIG. 7 is a rear view of FIG. 5;

FIG. 8 is a perspective view thereof of the amusement ride disclosed in FIG. 5, the undisclosed opposite side being a mirror image;

FIG. 9 is a fragmented perspective view of a third embodiment of the amusement ride showing my new design, the identical ride being omitted for ease of illustration only;

FIG. 10 is a front view of FIG. 9;

FIG. 11 is a rear view of FIG. 9;

FIG. 12 is a perspective view thereof of the amusement ride disclosed in FIG. 9, the undisclosed opposite side being a mirror image;

FIG. 13 is a fragmented perspective view of a fourth embodiment of the amusement ride showing my new design, the identical ride being omitted for ease of illustration only;

FIG. 14 is a front view of FIG. 13;

FIG. 15 is a rear view of FIG. 13; and,

FIG. 16 is a perspective view thereof of the amusement ride disclosed in FIG. 13, the undisclosed opposite side being a mirror image.

The broken line showing of the stand and/or platform is for illustrative purposes only and forms no part of the claimed design.
